his Attorney.

UNITED STATES PATENT OFFICE.

WILLIAM J. FOSTER, OF JERSEY CITY, NEW JERSEY, ASSIGNOR TO CHARLES GREEN, OF BROOKLYN, NEW YORK.

SEPARABLE-LEAF SAMPLE-BOOK.

1,247,104.

Specification of Letters Patent. Patented Nov. 20, 1917.

Application filed December 16, 1916. Serial No. 137,290.

To all whom it may concern:

Be it known that I, WILLIAM J. FOSTER, a citizen of the United States, and a resident of Jersey City, in the county of Hudson and 5 State of New Jersey, have invented certain new and useful Improvements in Separable-Leaf Sample-Books, of which the following is a specification.

This invention relates to sample books in 10 which a plurality of leaves are assembled, and more particularly to the means for detachably securing those leaves to each other, respectively. The object of my improvements is to provide fastening means for the 15 leaves of a sample book of the class specified in which the leaves may be readily joined and as readily detached, for the removal of any individual leaf, or for the insertion of another leaf at any desired location relative 20 to the other leaves.

With these objects in view my improvements comprise features illustrated in their preferred embodiment in the drawing accompanying this specification wherein—

25 Figure 1 is a perspective view of a sample book provided with my improved fastening means; Fig. 2 is a perspective view of portions of two leaves of a sample book showing said fastening means detached and about 30 to be assembled; Fig. 3 is a similar view showing the first step in assembling; Fig. 4 is a similar view showing a further step in assembling; and Fig. 5 illustrates the completion of assembly. Figs. 2 to 5 inclusive 35 are to a uniform scale, larger than that of Fig. 1.

In accordance with my improvements, I provide at one edge of a given sheet, as 2, means extending outwardly therefrom and 40 which means I have illustrated as a tongue or tongues, 3, projecting preferably at right angles from said edge. Also preferably, I form said tongue integral with sheet 2, although it is obvious that, as well known in 45 the art, said tongue may be formed of a separate portion of similar material to said sheet, or of other material if desired, and attached to the sheet by some well-known means, not shown.

50 Near the edge of a second sheet, 4, I provide holding means adapted to engage the outwardly extending tongue 3 of sheet 2. This holding means I have illustrated as a slot, 5, near edge 6 of said second sheet 4, 55 and said slot is preferably parallel with edge

6. For convenience in folding the leaves one upon another after they are hinged together, I preferably form a crease, 9, in sheet 4, near and parallel to edge 6 thereof, and preferably coincident with slot 5. 60

For fastening tongue 3 to leaf 2 after the engagement of said tongue with the holding means 5 of sheet 4, I provide slot 7 in said sheet 2. Said slot is preferably parallel with edge 8 of sheet 2, from which said 65 tongue extends, and is located at a distance from said edge 8, approximately the same as the distance of slot 5 from edge 6 of sheet 4. Said slot 7 corresponds in position with and is adapted to receive and hold 70 tongue 3, when said tongue has been passed through slot 5 in leaf 4 and folded around that portion of said leaf lying between slot 5 and edge 6.

In assembling the leaves of my improved 75 sample book, the edge of one leaf, as 2, overlaps the edge of another leaf, as 4, when said leaves are laid out flat; tongue 3 of the first leaf is then passed through slot 5 in the second leaf and folded around the edge 80 portion thereof; then said tongue 3 is passed into slot 7 of the first leaf, whereby the two leaves are securely locked together, (Fig. 5,) when they may be folded along the line of 85 crease 9 of leaf 4.

I claim:

1. A sample book comprising a plurality of detachable leaves, an edge of one leaf overlapped by an edge of a second leaf, a tongue extending outwardly from the overlapped edge of the first leaf, a slot in the overlapping edge of said second leaf adapted to receive the tongue of said first leaf, and a slot in said first leaf positioned and adapted to receive said tongue after it has 90 been passed through the slot in said second leaf. 95

2. In a sample book comprising a plurality of leaves, means for detachably connecting the adjoining edges of two leaves 100 including in combination a hinge member at the edge of one leaf coextensive with said edge, formed by folding the edge portion of said leaf onto the body thereof, a slot through said leaf in the line of folding, a 105 tongue extending outwardly from the adjacent edge of the second leaf, said edge being coextensive with the hinge member of said first leaf, said tongue being adapted for insertion through said slot and for folding 110

over said hinge member, and a slot in said second leaf, opposite said tongue and adjacent the infolded edge of said first leaf, adapted to receive the folded over end of 5 said tongue.

Signed at New York, Manhattan bor- ough, in the county of New York and State

of New York, this 30th day of October, 1916, before two subscribing witnesses.

WILLIAM J. FOSTER.

Witnesses:

WILBERT M. STONE,
CHAS. W. LA RUE.
